UNITED STATES PATENT OFFICE.

FREDERICK E. LOESCHER, OF HARRISON, HARRY P. JAENIKE, OF BROOKLYN, AND ELMER I. DAUGHERTY, OF ELMHURST, NEW YORK.

VOLUME-REDUCING VALVE CAP.

Application filed October 16, 1920. Serial No. 417,460.

To all whom it may concern:

Be it known that we, FREDERICK E. LOESCHER, HARRY P. JAENIKE, and ELMER I. DAUGHERTY, citizens of the United States, 5 residing at, respectively, Harrison, in the county of Westchester and State of New York, and at Brooklyn, in the county of Kings and State of New York, and at Elmhurst, in the county of Queens and State of 10 New York, have invented new and useful Improvements in Volume-Reducing Valve Caps, of which the following is a specification.

This invention relates to certain new and 15 useful improvements in valves, and its primary object is to reduce the volume capacity of a valve by providing means for automatically arresting the opening movement of the valve actuating stem before the valve is permitted to reach full open position.

Another object of the invention is to provide variable means for arresting the opening movement of the valve stem, in order that the valve may be halted at different 25 points in its movement from closed to complete open position.

A further object of the invention is to so construct the valve arresting means that the same may be applied to different types of 30 valves without requiring material changes in the construction and arrangement of the valve parts.

Other objects of this invention are: to provide a device of this character adaptable 35 to valves of standard construction, comprising few parts, simple in design, and efficient in operation.

With these and other objects in view, which will become apparent as the description 40 proceeds, the invention resides in the construction, combination and arrangement of parts, hereinafter more fully described and claimed, and illustrated in the accompanying drawings, in which like characters 45 of reference indicate like parts throughout the several figures, of which:

Fig. 1 is a view partly in vertical section, of a valve having our invention applied thereto;

50 Fig. 2 is a perspective view showing the volume reducing cap disengaged from the valve body to expose parts carried by the valve stem and normally contained within said cap;

55 Fig. 3 is a sectional view through a por-

tion of a valve having a modified form of our invention applied thereto; and

Fig. 4 is a perspective view of parts shown in Fig. 3.

In the illustrated embodiment characterizing this invention we have shown a valve including a rotary valve stem of the rising type, comprising a valve body 5, valve bonnet 6, valve stem 7, and valve bonnet cap 8. As is usual in valves of this type, the lower 60 portion of the valve stem is threaded through the bonnet as indicated at 9, while the upper end of the stem is equipped with a suitable handle 10. The valve proper is not shown, and the valve may be of the globe, gate, or 65 angle type, commonly employed in connection with rotary rising valve stems, as clearly shown in Fig. 1 of the drawings.

In applying our invention to a valve of the type above referred to we provide a cap 75 11, the lower end of which is open and threadedly engaged with the upper end of the bonnet cap 8, as indicated at 12. The upper end of the cap 11, which we will hereinafter term the volume reducing cap, is 80 apertured centrally to permit of the passage of the valve stem therethrough and its top is spaced an appreciable distance from the top of the bonnet cap. At a point immediately above said bonnet cap 8 the valve 85 stem 7 is provided with a fixed washer-seat 13, on which a plurality of removable washers 14 are adapted to be supported. The arrangement is such that the amount of clearance between the outer or uppermost 90 washer may be varied by increasing or decreasing the number of washers.

In practice, the valve stem when rotated in a valve opening direction rises vertically carrying with it the washers 14, which are 95 adapted to seat against the top of the volume reducing cap 11, thus arresting further rotation of the stem and halting the opening movement of the valve before the latter reaches full open position. By varying 100 the number of washers 14, to advance or retard the time of contact between the outermost washer and the cap 11, the extent to which the valve may be opened is regulated.

In Fig. 3, wherein a modification of the 105 invention is shown, the valve stem 7' is of the rotary nonrising type, and the portion thereof which extends into the volume reducing cap 11' is threaded as at 12' to receive thereon a movable washer-seat 13' on 110

which the washers 14' are arranged. To prevent rotation of the washer-seat 13' with the valve stem, said seat is formed with vertical grooves 15 receiving therein complementary vertical ribs 16 projecting from the inner wall of the cap 11'.

In the operation of this type of valve, when the valve stem 7' is rotated in a valve opening direction, the washer-seat 13' moves vertically thereon until the uppermost washer 14' seats against the top of the cap 11'.

From the foregoing it is apparent that we have designed a volume reducing means readily adaptable to various types of valves, eliminating the inherent deficiencies of those now in use, efficient in operation, simple in construction, and inexpensive to manufacture and install.

Although in the foregoing, certain elements may have been set forth as best adapted to perform the functions allotted to them, nevertheless, it is to be understood that various minor changes as to form, substance, etc., may be resorted to within the scope of the appended claims without departing from or sacrificing any of the principles of this invention.

Having thus described our invention, and without enumerating variations and equivalents, what we desire protected by Letters Patent is as set forth in the following claims:

1. In a reducing valve, the combination

with a valve, valve body, and valve stem, of a cap attached to said body and receiving the stem therethrough, and means carried by the stem within the cap and movable into engagement with the latter to arrest the opening movement of the valve before it reaches full open position, said means consisting of a stop member composed of a plurality of sections, the number of which may be increased or decreased to advance or retard the arresting of the valve.

2. A volume reducing valve provided with complementary stop members disposed to be brought into abutting engagement by movement of the valve to open position, one of said stop members being composed of sections variable in number to regulate the extent to which the valve may be opened.

3. A volume reducing valve provided with complementary stops disposed to be brought into abutting engagement by movement of the valve to open position, one of said stops being variable in size to regulate the extent to which the valve may be opened.

4. The combination with a valve; of a stop comprising members variable in number to regulate the extent to which the valve may be opened.

FREDERICK E. LOESCHER.
HARRY P. JAENIKE.
ELMER I. DAUGHERTY.
